EARTH BORING TOOL

Clarence E. Reed, Wichita, Kans., assignor to
 Chicago Pneumatic Tool Company, New York,
 N. Y., a corporation of New Jersey

Application February 26, 1940, Serial No. 320,955

9 Claims. (Cl. 255—71)

This invention relates to earth boring tools of the type in which a plurality of independently rotary cutters are mounted on the underside of a bit head. Some of these cutters, and particularly those cutters at the side of the bit head for disintegrating the area at the side of the hole, are rotatable about axes which are inclined to the horizontal.

Cutters which rotate about such inclined axes have imposed upon them operating forces which tend to twist the cutter upon its spindle in such manner that the axis of the cutter and the axis of the spindle are not in alignment. The consequent disalignment impairs the cutting efficiency of the cutter and causes destructive wear upon the cutter bearings and upon the cutter teeth. An important feature of the present invention is the provision of means which will tend to maintain the axis of the cutter in alignment with the axis of the spindle.

Other features of the invention will be apparent from the following description.

In the drawings:

Figure 1 is a plan view of the underside of an earth boring tool embodying the invention.

Fig. 2 is a section on the line 2—2 of Fig. 1, only the cutters in the sectional plane being shown.

Fig. 3 is a side elevation of the hanger appearing in Fig. 2.

Fig. 4 is a side elevation of the removable spindle portion of Fig. 2.

Fig. 5 is a section on the line 5—5 of Fig. 1.

Fig. 6 is a section on the line 6—6 of Fig. 1.

Fig. 7 is an elevation of the removable spindle portion of Fig. 5.

Fig. 7a is a fragmental section through the cutter of Fig. 5.

Fig. 8 is an elevation of the bridge member appearing at the righthand end of the spindle of Fig. 2.

Fig. 9 is a section of a modified arrangement of the assembly appearing in Fig. 2.

Fig. 10 is a side elevation of the hanger of Fig. 9.

Fig. 11 is a side elevation of the removable spindle portion of Fig. 9.

Referring first to the embodiment of the invention appearing in Figs. 1 to 8, inclusive, this earth boring tool includes the side cutters 1, 2, and 3 and the central cutter 4. The side cutters 1, 2, and 3 are rotatable about axes which lie in planes which pass through the axis x—x of the bit head 5, and which are 120° apart. The central cutter 4 rotates about an axis which lies in

the plane containing the axis of rotation of the side cutter 1. All of the axes of rotation of the side cutters are inclined, so that they converge downwardly and inwardly of the drill toward the bit head axis. It is preferable that the axis of rotation of the center cutter 4 also incline downwardly and inwardly of the drill. The teeth which are formed upon the exteriors of these several cutters preferably are of the formation disclosed in Reed Reissue Patent No. 15,126, dated June 14, 1921.

The side cutter 1 is preferably of frusto-conical shape, the larger diameter of this cutter being disposed outwardly of the bit head. This cutter disintegrates an annular area at the side of the hole which includes clearance for the bit head, and this area preferably inclines downwardly and inwardly toward the center of the hole. The cutter is exteriorly formed with teeth 1a extending throughout the axial length of the cutter.

The central cutter 4 is preferably of frusto-conical formation, and in the relationship shown, it disintegrates a circular area at the center of the hole which is horizontal, or perpendicular to the drill axis. As appears from Fig. 2, the area disintegrated by the central cutter 4 will be higher than the inner part of the area disintegrated by the side cutter 1. Annular grooves 4b may be formed in the exterior of the cutter 4, so that the teeth lengthwise of the cutter are notched.

To support the side cutter 1 and the central cutter 4 from the drill head 5, a hanger 6 and a removable spindle member 7 are provided. The hanger 6 is of the formation disclosed and claimed in Reed Patent No. 2,058,625, dated October 27, 1936. It includes a shank 8 which may be affixed to the side of the bit head, and a spindle 9 projecting laterally from the lower end thereof. Through the spindle 9 is formed a bore hole to receive the stem 10 of the removable spindle member 7. The spindle member 7 also includes a flange 11 having a face 12 which bears against the free end face of the spindle 9, and includes a spindle 13 which projects from the side face of the flange 11 which is opposite from the stem 10.

To rotatably mount the cutter 1, the spindle 9 at its base has formed therein a groove 14 to constitute a raceway for frusto-conical, anti-friction roller bearings 15. The bottom of the groove 14 is of conical formation converging toward the free end of the spindle 9. At its free end, the spindle 9 is formed with an exterior cylindrical surface 16 upon which roll the cylindrical anti-friction roller bearings 17. The roller

bearings 17 are prevented from movement toward the free end of spindle 9 by the surface 12 of the flange 11 which overlies the ends of the rollers. At its outer periphery the flange 11 is formed with a cylindrical surface 18.

Cutter 1 is formed internally with conical shaped surface 20 which bears upon the roller bearings 15. This cutter also includes a counterbored cylindrical surface 21 which constitutes a raceway for the roller bearings 17. At its innermost end the cutter is formed with a further enlarged counterbore providing a cylindrical surface 22 which bears frictionally upon the peripheral surface 18 of the flange 11. The shoulder 23, which is presented between the counterbore surfaces 21 and 22, bears frictionally against surface 12 of the flange 11. Adjacent the hanger 6 the cutter 1 is provided with a surface 24 which frictionally bears against the inner face of the hanger.

To assemble the cutter 1, the roller bearings 15 are first placed in position in the raceway 14. The cutter 1 is then passed over the free end of the spindle 9 so as to bring the surface 20 thereof upon the roller bearings 15. Roller bearings 17 are then inserted in place between the surface 16 of the spindle and the internal surface 21 of the cutter. The removable spindle member 7 is then placed in position by inserting its stem 19 in the bore through the spindle 9, and welding 23' is applied at its end to hold the removable spindle member in place. The cutter 1 is positively retained in place upon the spindle 9 by the abutting surfaces 12 and 23. In order that the roller bearings 17 will not sustain any inward end thrust of the cutter, they should be of less axial length than the raceway surface 21. Outward end thrust of the cutter is sustained by the surface 24 of the cutter.

The central cutter 4, in accordance with the invention, frictionally bears upon the exterior of the projecting spindle 13 of the removable spindle member 7. In order to reduce the wear upon the spindle and cutter, it is desirable that the spindle bearing surface and that the internal bearing surface of the cutter be hardened by any hard-facing material, as is indicated at 25 and 26, respectively. The clearance of the running fit of the center cutter on its spindle should be about .010 inch. To retain the cutter 4 upon its spindle 13, a bridge member 27 may be affixed, as by welding, upon the reduced end portion 28 of the spindle. This bridge member 27 overlies the end of the cutter 4, so that the cutter frictionally bears against it.

The cutter 2 is provided exteriorly at the base part thereof with teeth 2a which are of generally frusto-conical formation, and is provided at the inner part thereof with teeth 2c separated from the teeth 2a by a deep, wide groove 2b. The teeth 2a are of the same diameter as the teeth 1a at the larger end of cutter 1, and these teeth 2a act upon the same inclined area as that disintegrated by the teeth 1a, but since the teeth 2a are not as long as teeth 1a, only the outer portion of this area is disintegrated by them. The teeth 2c cut an annular area which is next inwardly from the inner extremity of the annular area cut by the teeth 1a. These teeth 2c are at a sharp angle with respect to the cutter, so that the area cut thereby inclines upwardly toward the outer extremity of the area cut by the central cutter 4. However, the area which is cut by the teeth 2c does not extend inwardly to

the area cut by the teeth of cutter 4, an annular area existing between them.

To rotatably support the cutter 2, a hanger 30 having a removable portion 31 is provided. The hanger is formed with a shank 32 by which it may be affixed to the side of the bit head 5, and is formed with a spindle 33 having a bore therethrough to receive the stem 34 of the removable portion 31. The spindle 33 has formed therein, at the base portion thereof, a groove 35 constituting a raceway to receive frusto-conical anti-friction roller bearings 36. The bottom of this raceway 35 converges toward the free end of the spindle. Toward the free end of the spindle 33 is formed a second groove 37, the bottom of which is a cylindrical surface, to receive cylindrical anti-friction roller bearings 38. The extreme end of the spindle is formed with a cylindrical exterior surface 39.

The interior of the cutter 2 is formed with a frusto-conical surface 40 at the base portion thereof to bear upon the roller bearings 36, and is formed centrally of the length of the cutter with a cylindrical surface 41 to bear upon the anti-friction rollers 38. Slightly inwardly from the small end of the cutter is formed an internal flange 42 which provides an inwardly facing surface 43, Fig. 7a, which will frictionally bear upon the exterior surface 39 of spindle 33. Immediately within the inner end of the cutter is formed a counterbore providing an internal cylindrical surface 44 and a shouldered surface 45. The surface 44 bears frictionally upon the peripheral surface 46 of the flange 47 of the removable portion 31. Surface 45 bears against the inner surfaces 48 of flange 47, these surfaces being perpendicular to the axis of the cutter.

In order to assemble the cutter 2, the roller bearings 36 and 38 are first placed in their respective raceways 35 and 37. The cutter 2 is then passed over and upon them, this also bringing internal surface 43 of the cutter upon the surface 39 of spindle 33. The stem 34 of the removable portion 31 is then inserted in the bore of the spindle 33 and is affixed in place by welding. When so assembled, the cutter 2 will be prevented from displacement off of its spindle by reason of the frictional end bearing surfaces at 45 and 48. Inward end thrusts of cutter 2 are sustained by these surfaces 45 and 48, while outward end thrusts of the cutter are sustained by the end face 49 of the cutter bearing against the hanger 30.

The cutter 3 is formed at its base portion with teeth 3a and at its smaller end with teeth 3c separated by a groove 3b from teeth 3a. The teeth 3a are of the same diameter as the teeth 1a and 2a, and act upon the same area on the bottom of the bore hole which is cut by the teeth 1a and 2a. Teeth 3a, however, are slightly longer than the teeth 2a, although not as long as teeth 1a, so that the area cut by the teeth 2a is extended further inwardly to the center of the drill hole by the teeth 3a. Teeth 3c cut the area at the bottom of the bore hole just outside of the area cut by the teeth of cutter 4, and extending up to the inner edge of the area cut by the teeth 2a. This is the area left uncut between teeth 2a and cutter 4. This area cut by the teeth 3c is an inward and upward continuation of the inclined area cut by the teeth 2c inasmuch as these two areas lie upon the same generally conical surface between the inner edge of the area cut by teeth 1a, and the outer edge of the area cut by the teeth of cutter 4.

The support for the cutter 3 is identical with the support for the cutter 2, so that a hanger and removable portion fabricated for the cutter 2 will serve for the cutter 3. In this respect, the hanger 50 for the cutter 3 includes a spindle 51 providing a raceway for the frusto-conical roller bearings 52, and providing a raceway for the cylindrical roller bearings 53. The interior of the cutter 3 is formed with a flange 54 which frictionally bears upon the free end of the spindle 51. The removable portion 55 is formed with a flange 56, against which the cutter frictionally bears, corresponding to the identically shaped surfaces for cutter 2. It will be understood that the internal bearing surfaces of the cutter 3 are shaped identically with the internal bearing surfaces of the cutter 2, the only difference between these cutters residing in the formation of and location of the particular cutter teeth upon their exteriors.

The cutters 1, 2, 3, and 4 may be assembled upon their spindles while the hangers 6, 30, and 50 are apart from the bit head. Before these hangers are affixed to the bit head, the flushing fluid distributing member 57 should be affixed in the hole at the bottom of the bit head. The hangers 30 and 50 with their cutters 2 and 3 should then be affixed to the bit head. Thereafter, the assembly, including cutters 1 and 4, should be placed in position by affixing hanger 6 to the bit head. When the assembly is complete, the end faces of the bridge member 27 will bear against the inner faces of the removable portions 31 and 55. The connection so established between the inner ends of the three cutter supports will serve to strengthen them by the mutual support they receive from each other. This feature is disclosed and claimed in Reed application Serial No. 312,147, filed on January 2, 1940.

The internal bearing arrangement for the side cutters 1, 2, and 3 is of importance and constitutes a feature of the present invention because the frictional and anti-frictional bearings serve to sustain the forces imposed upon the cutter when in use. When the operating load is imposed on a cutter positioned as shown, its spindle axis being inclined to the horizontal on the order of 30°, the bottom of the cutter tends to move outwardly from the drill axis, and the upper part of the cutter tends to move inwardly toward the drill axis, and the cutter accordingly tends to move out of axial alignment with its spindle axis. This tendency of the cutter to move out of axial alignment with the spindle is resisted by the cylindrical roller bearings at the inner end of the cutter which increase the free rolling of the cutter. The large frictional bearing surfaces at the inner end of the cutter also assist in overcoming the tendency of the cutter to twist upon its spindle. The bearing arrangement of the invention therefore tends to maintain the cutter axis coincident with the spindle axis and less wear upon the bearings and improved cutting results.

This feature of the invention of providing bearings for side cutters which will maintain axial alignment of the cutters on their spindles is also attained by the modified construction of Figs. 9 to 11. The assembly shown in Fig. 9 may take the place of the assembly shown in Fig. 2, and includes a side cutter 60 and a central cutter 61. To support these cutters, a hanger 62 and a removable spindle member 63 are provided, this member having a stem 64 which enters a bore hole through the spindle 65 of the hanger. Into the exterior of spindle 65 is formed a groove 66

having a cylindrical bottom surface to constitute a raceway for cylindrical anti-friction roller bearings 67.

The removable spindle member 63 is provided with a flange 69 which provides upon its exterior a cylindrical surface 70 of large diameter and a cylindrical surface 71 of smaller diameter located nearer the stem 64. An annular recess 72 is formed in the side face 73 of flange 69 adjacent the stem 64 to receive the free end of the spindle 65. The surface 71 serves as a raceway for cylindrical anti-friction bearings 74.

Internally of cutter 60 are formed a cylindrical surface 76 to bear upon bearings 67, and a cylindrical surface 77. The inner portion of this surface 77 bears upon the bearings 74 and the outer portion of surface 77 bears frictionally upon the peripheral surface 70 of flange 69 of the removable spindle member 63. The shoulder surface 78 formed within the cutter between surfaces 76 and 77 bears upon the face 73 of flange 69, and this serves to retain the cutter against inward axial movement. The surface 79 upon the cutter serves to sustain outward end thrusts of the cutter by bearing against the hanger 62.

To assemble the cutter 60, the bearings 67 are first placed upon the raceway 66 and the cutter is then placed in position by passage over the free end of the spindle 65. Then the removable spindle member 63 with rollers 74 in place upon surface 71 is placed in position by inserting the stem 64 through the bore hole of the spindle 65, this bringing the rollers 74 and the surface 70 within the surface 77 of the cutter.

The central cutter 61 rotates upon spindle 80, forming a part of member 63, and is retained in place upon this spindle by a bridge member 81 located upon the reduced end portion 82. The bearing surface of spindle 80 and the internal bearing surface of cutter 61 may have hardening material applied to them to reduce wear.

In the several embodiments of the invention which are illustrated, the side cutters are rotatable about axes which incline downwardly and inwardly of the drill. The feature of providing bearings for these cutters which will resist the tendency of the cutters to twist out of axial alignment with their spindles may be applied as well to the cutters of core bits in which type of drill the cutters rotate about axes which incline upwardly and inwardly of the drill. In either situation, the axes of rotation of the cutters are inclined, and the same operating forces are imposed upon them.

Various departures may be made from the precise arrangements illustrated, both as to the positioning of the cutters and as to the bearings of the cutters. For example, although the center cutter 4 is shown with its axis of rotation in the same vertical plane as the axis of its associated side cutter 1, it may also be positioned in the assembly with its axis offset slightly from a vertical plane through the bit axis. Such positioning of the center cutter axis is desirable in some formations in which more than the usual amount of scraping of the cutter teeth edges is required for fast cutting. This offset positioning of the center cutter is illustrated and claimed in my co-pending application Ser. No. 371,446 filed on Dec. 23, 1940.

I claim:

1. An annular side cutter assembly for an earth boring drill comprising a rotary cutter having two cutting zones inclined to each other, a support having projecting laterally and downwardly there-

from a spindle for rotatably mounting the cutter, a row of anti-friction roller bearings between the cutter and the spindle at the end of the cutter to be disposed outwardly of the drill, intersecting pairs of friction bearing surfaces between the cutter and the spindle at the inner end of the cutter bore, and a row of cylindrical roller bearings between the cutter and the spindle and located within the cutter between said anti-friction roller bearings and said friction bearing surfaces, said spindle including a removable portion having a flange and said cutter having an internal flange which frictionally bears against said spindle flange to afford one pair of said intersecting friction bearing surfaces and take end thrusts of the cutter inwardly of the drill.

2. In an earth boring drill, three side cutters of uniform diameter, of different axial lengths of toothed exterior surface, tapered rollers between said cutters and spindles for the cutters taking radial loads and thrusts outwardly of the drill, a larger diameter cylindrical roller bearing in one cutter, and central independently rotating cutter means having a hard faced bore and a hard faced spindle therefor.

3. In a rotary cutter and spindle assembly for an earth boring drill, a roller cutter having a bore extending through said cutter and mounted on a spindle, the axis of which inclines to the axis of the drill, anti-friction roller bearings between said cutter and spindle at the high end of said inclined spindle and at the lower end portion of said spindle a cylindrical roller bearing of larger diameter than said anti-friction roller bearing, and end thrust frictional bearing surfaces on the cutter and the spindle.

4. A side cutter assembly for an earth boring drill comprising a rotary cutter, a spindle for rotatably mounting the cutter, a row of anti-friction roller bearings between the cutter and the spindle at the end of the cutter to be disposed outwardly of the drill, a cylindrical friction bearing between the cutter and the spindle at the other end of the cutter, a row of cylindrical roller bearings between the cutter and the spindle and located within the cutter between said anti-friction roller bearings and said friction bearing, and a frictional end thrust bearing between the cutter and spindle disposed between said row of anti-friction roller bearings and the row of cylindrical roller bearings.

5. An earth boring drill comprising two side roller cutter assemblies, each assembly including a side roller cutter having a bore extending through the cutter and having two cutting zones inclined to each other, a support having projecting laterally and downwardly therefrom a spindle, a row of tapered roller bearings and a row of cylindrical roller bearings between said cutter and spindle, and intersecting complementary frictional bearing surfaces at one end of the cutter and spindle securing said cutter and roller bearings on said spindle; a member connecting the

inner ends of said assemblies, and one other cutter assembly comprising two cutters, one being a side cutter and the other a center cutter, a spindle therefor and a drill head connected to said last mentioned spindle and said supports and supporting said assemblies.

6. In an earth boring drill three side cutters of uniform diameter, of different axial lengths of cutting surface and one of said cutters recessed at its inner face, another cutter projecting within said recess, said another cutter being mounted upon a spindle and extending to approximately the longitudinal axis of the drill, rolling radial bearings and rolling end thrust bearings between the said side cutters and spindles therefor, and hard faced frictional bearing surfaces on said another cutter and the spindle therefor.

7. In an earth boring drill, a side rotary cutter 20 and spindle positioned with their axes inclined to the axis of the drill, said rotary cutter having two cutting zones inclined to each other, anti-friction roller bearings between said cutter and spindle at the high end of said inclined spindle 25 and at the lower portion of said spindle a larger diameter bearing than the previously recited bearings taking lateral thrusts of said cutter, interengaging end thrust bearing surfaces on said cutter and spindle, and another spindle portion 30 inwardly from said larger diameter bearing having a hardened face periphery, and a cutter on said spindle portion.

8. In an earth boring drill, a side rotary cutter and spindle positioned with their axes inclined to 35 the axis of the drill, said rotary cutter having two cutting zones inclined to each other, anti-friction roller bearings between said cutter and spindle at the high end of said inclined spindle and at the lower portion of said spindle a larger diameter bearing than the previously recited bearings 40 taking lateral thrusts of said cutter, interengaging end thrust bearing surfaces on said cutter and spindle, and another spindle portion inwardly from said larger diameter bearing having 45 a hardened face periphery, and a cutter on said spindle portion, said larger diameter bearing additionally comprising cylindrical roller bearings and frictional bearing surfaces.

9. An earth boring drill comprising three cutters, each having substantially the same amount of total cutting edges annularly arranged, roller radial bearings and rolling end thrust bearings for said cutters, spindles for said cutters and frictional abutting surfaces retaining said cutters 50 on said roller bearings and said spindles, and another cutter between one of said three cutters and the drill axis positioned under overhanging portions of said three cutters, the spindle for said another cutter and the bore of said cutter 55 being hard faced, said cutters disintegrating the entire area of the bottom of the hole and including clearance at the side of the drill.

CLARENCE E. REED.
